UNITED STATES PATENT OFFICE.

JACOB LEVIN, OF NEW YORK, N. Y., ASSIGNOR TO THE LEBROS MANUFACTURING CO., INC., OF NEW YORK, N. Y., A CORPORATION OF MASSACHUSETTS.

DESIGN FOR A BEVERAGE PREPARING AND DISPENSING STAND.

Application filed October 18, 1923. Serial No. 7,542. Term of patent 14 years.

To all whom it may concern:

Be it known that I, JACOB LEVIN, a citizen of the United States, residing at 450 East 140 Street, city of New York, in the county of New York and State of New York, have invented a new, original, and ornamental Design for a Beverage Preparing and Dispensing Stand, of which the following is a specification, reference being had to the accompanying drawings, forming part thereof.

Fig. 1 of the drawings is a front elevation showing my new design; and,

Fig. 2 is a side elevation of the same.

I claim:

The ornamental design for a beverage preparing and dispensing stand as shown.

JACOB LEVIN.
